(57) **CLAIM**

The ornamental design for a raw dough product, as shown and described.

DESCRIPTION

FIG. 1 is a perspective view of a raw dough product showing my new design;

FIG. 2 is a front elevational view thereof;

FIG. 3 is a left side elevational view thereof;

FIG. 4 is a top plan view thereof; and,

FIG. 5 is a bottom plan view thereof.

It is understood that the broken linework on the top, bottom and sides of FIGS. 1, 3, 4 and 5 indicate the product has multiple layers.
